UNITED STATES PATENT OFFICE.

WALTER H. PICKEL, OF BICKNELL, INDIANA.

SWITCH-OPERATING MECHANISM.

Application filed December 17, 1923. Serial No. 681,249.

To all whom it may concern:

Be it known that I, WALTER H. PICKEL, a citizen of the United States, residing at Bicknell, in the county of Knox and State 5 of Indiana, have invented certain new and useful Improvements in Switch-Operating Mechanisms; and I do declare the following to be a full, clear, and exact description of the invention, such as will enable others 10 skilled in the art to which it appertains to make and use the same.

My invention relates to improvements in operating mechanisms for railway switches, the device being primarily designed for use 15 in connection with mine railways. The switches commonly used on railways of this character, when set to send a car traveling in one direction either along the main line, or onto the switch, will not permit cars 20 to travel in the opposite direction on both the main line and the switch, without injuring the latter, but it is the object of my invention to provide a switch throwing mechanism which will overcome this difficulty, without the use of springs.

With the foregoing in view, the invention resides in the novel subject matter hereinafter described and claimed, the description being supplemented by the accompanying 30 drawing.

Figure 1 is a plan view.

Figure 2 is a transverse sectional view showing the switch open, as in Fig. 1.

Figure 3 is a view similar to Fig. 2 but 35 illustrating the relation of parts when the switch is closed by a car on the main track, traveling in the direction of the arrow A of Fig. 1.

Figure 4 is a detail vertical section showing the switch-throwing mechanism in the opposite position from that disclosed in Fig. 2.

In the drawing above briefly described, the numerals 1 designate the usual switch 40 tongues which are connected by a bridle bar 2. This bridle bar has its outer end connected by a rod or link 3, with the lower end of a vertically swinging lever 4, the central portion of this lever being formed 45 with a fulcrum-receiving opening 5 whose upper edge is shaped to provide a pair of laterally spaced fulcrum seats 6. A fulcrum bolt or the like 7 passes through the opening 5 and is receivable in either of the 50 seats 6. This fulcrum is here shown, supported by a pair of parallel plates 8 which

rise from a base plate 9 secured upon suitable ties or the like, said plate 9 having a slot 10 through which the lever 4 passes.

A coupling member 11 has a flared socket 12 formed in its lower end, and the upper end of the lever 4 is loosely pivoted in said socket, as indicated at 13, so that the coupling member may move to either side of the center of the lever 4, as will be obvious by comparing Figs. 3 and 4. The upper end of the coupling member 11 is formed with a similar flared socket 14 in which the lower end of an arm 15 is loosely pivoted as indicated at 16, the outer 70 end of said arm having an adjustable weight 17.

The construction above described, offsets the weight 17 to a great extent from the fulcrum 7, regardless of the direction in which the arm 15 is thrown, to open or close the switch. Thus, even though one of the tongues 1 may be moved by a car into contact with the rail from which it was previously spaced, the movement of 80 parts will not be sufficient to reverse the position of the switch-throwing mechanism. Consequently, as soon as the car passes, the switch will be again returned to its initial position. For instance, if the switch is open 85 as shown in Fig. 1, the operating mechanism stands as shown in Fig. 2. If a car now travels in the direction of the arrow A (Fig. 1) and forces the tongues 1 to the right, the operating mechanism assumes the 90 position disclosed in Fig. 3 and as soon as the car passes, all parts return to their initial positions, under the influence of the weight 17.

As excellent results may be obtained from 95 the details disclosed, these details are preferably followed, but within the scope of the invention as claimed, numerous minor changes may be made.

I claim:

1. A switch operating mechanism comprising a lever whose lower end is adapted for connection to the outer end of a bridle bar, means for fulcruming said lever between its ends for movement to oppositely inclined positions, a coupling member pivotally connected at its lower portion to the upper end of said lever and movable to opposite sides of the central line of said lever, a vertically swinging weight-carrying arm 110 pivotally connected with the upper portion of said coupling member and movable to op-

posite sides of the central line of said coupling member, and means for limiting the movement of said arm with respect to said coupling member and of the latter with respect to said lever.

2. A switch operating mechanism comprising a lever whose lower end is adapted for connection to the outer end of a bridle bar, means for fulcruming said lever between its ends for movement to oppositely inclined positions, a coupling member having a flared socket in its lower end in which the upper end of said lever is loosely pivoted to permit swinging of said coupling member to opposite sides of said lever, the upper end of said coupling member also having a flared socket, and a weight-carrying arm loosely pivoted in the upper socket for movement to either side of said coupling member.

3. A switch operating mechanism comprising a lever whose lower end is adapted for connection to the outer end of a bridle bar, the intermediate portion of said lever having a fulcrum-receiving opening whose upper edge wall is formed with laterally spaced fulcrum seats, a stationarily supported fulcrum passing through said opening and receivable in either of said seats according to the direction in which said lever is swung, a coupling member having a flared socket in its lower end in which the upper end of said lever is loosely pivoted to permit swinging of said coupling member to opposite sides of said lever, the upper end of said coupling member also having a flared socket, and a weight-carrying arm loosely pivoted in the upper socket for movement to either side of said coupling member.

is swung, a vertically swinging weight-carrying arm pivotally connected with the upper end of said lever and movable in a common plane therewith to opposite sides of a central line of said lever, and means for limiting the movement of said arm with respect to said lever.

4. A switch operating mechanism comprising a lever whose lower end is adapted for connection to the outer end of a bridle bar, the intermediate portion of said lever having a fulcrum-receiving opening whose upper edge wall is formed with laterally spaced fulcrum seats, a stationarily supported fulcrum passing through said opening and receivable in either of said seats according to the direction in which said lever is swung, a coupling member having a flared socket in its lower end in which the upper end of said lever is loosely pivoted to permit swinging of said coupling member to opposite sides of said lever, the upper end of said coupling member also having a flared socket, and a weight-carrying arm loosely pivoted in the upper socket for movement to either side of said coupling member.

In testimony whereof I have hereunto affixed my signature.

WALTER H. PICKEL.
